[57] CLAIM

The ornamental design for a table, as shown and described.

DESCRIPTION

FIG. 1 is a perspective view of a table, showing my design.

FIG. 2 is a bottom plan view thereof.

FIG. 3 is a side elevational view.

The side opposite that shown in FIG. 3 has the appearance of that shown in FIG. 3.

FIG. 1.

FIG. 2.

FIG. 3.
